UNITED STATES PATENT OFFICE.

CLIVE W. LANPHERE, OF NEW YORK, N. Y.

INTERLOCKING AUTOMATIC LOCK.

Application filed February 6, 1923. Serial No. 617,235.

To all whom it may concern:

Be it known that I, CLIVE W. LANPHERE, a citizen of the United States, residing at New York, county of New York, and State of New York, have invented certain new and useful Improvements in Interlocking Automatic Locks, fully described and represented in the following specification and the accompanying drawings, forming a part of the same.

This invention relates to that class of door-locks in which a curved bolt is used to make a strong connection between the lock-casing and the guard or keeper upon the door-frame.

The curved bolt is fitted to work through two apertures upon the lock-case and two corresponding apertures upon the adjoining face of the guard, the entire bolt when unlocked lying inside of the lock-case, and its middle portion being looped around a post in the guard when the bolt is locked.

The chief object of the invention is to provide means to assure the automatic interlocking of the lock-bolt and the lock-guard when the door is pushed shut. One object is to avoid any partial interlocking of the bolt and its detent when the door is open.

Another object is to provide means whereby the shrinkage of the door or its frame may be compensated for by making the guard adjustable toward and away from the face of the lock, so as to maintain the normal relation of the lock and guard.

Another object is to block or prevent any movement of the bolt when engaged with the guard. Another object is to protect the guard from the action of a jimmy or similar tool. Other features will be referred to herein in connection with the drawing.

The chief object is effected by fitting a detent of special construction to engage the edge of the curved bolt, and controlling the operation of such detent by a tumbler which is moved by the bolt when fully retracted; and a tumbler which locks the bolt in its projected or interlocking position.

The means for blocking any movement of the bolt when projected from the lock-case, consists of a so-called bolt-tumbler which is arranged to engage a shoulder upon the bolt when the bolt is fully projected, and which tumbler is withdrawn from the bolt previ-

ous to retracting it, by an arm upon a key or lock-barrel which, when turned by a key or knob respectively, operates to withdraw the bolt-tumbler from the shoulder in the bolt before the retractive movement of the bolt is commenced.

The compensation for shrinkage is effected by making the guard or keeper adjustable upon the door-frame and preferably in two parts, whereby one may be rigidly attached to the door-frame and the other part adjustable thereto, so that it may be set close to the lock-face as desired.

The improvements will be understood by reference to the annexed drawing, in which Fig. 1 shows a lock with one side removed; and the bolt retracted within the lock-case; Fig. 2 shows the lock with its cover removed, the adjacent guard in section, and the bolt projected from the lock-case into the guard; Fig. 3 is a plan of the lock-case with its cover removed; Fig. 4 is a cross-section on line 4-4 in Fig. 1; Fig. 5 is a cross section on line 5-5 in Fig. 1; Fig. 6 is a cross section on line 6-6 in Fig. 2; Fig. 7 is a cross section on line 7-7 in Fig. 1; Fig. 8 is an edge view of the bolt and its attachments; Fig. 9 is a transverse section of a rim-lock with the door and lock-case adjoining; Fig. 10 shows the relation of the bolt-tumbler and tail when the bolt is retracted; and Fig. 11 is a plan of the lock-case with the cover removed, and a modified form of the bolt and the catch for manually holding the bolt inoperative, and shows the parts adjacent to the bolt-tongue with the means for automatically securing it in a locked position.

The lock-case 20 and the lock-guard 22 are fitted to slightly clear one another when the door 21 is closed, and a spring and detent are respectively provided to project and lock the bolt when retracted, and a releaser mechanism normally operates to release the bolt within the lock-case and project the tongue 24 of the bolt into the guard (as shown in Fig. 2).

The term "guard" where used herein, covers any form of keeper or lock-plate adapted to cooperate with the curved lock-bolt in the manner herein described.

Provision is made for such engagement of the guard and bolt by two apertures 25,

in the lock-face, and two corresponding apertures 26 in the face of the guard (as shown in Fig. 2).

The tongue 24 of the bolt is guided in a circular path by ribs 27 within the casing, and the bolt is held to its curved path, when the tongue is projected, by a tail-piece 46, extended from the inner end of the bolt between the ribs.

10 A stop 38 is provided upon the guide-rib of the raceway, to limit the retroactive movement of the tongue, and to set the notch 31 opposite the detent 32 as in Fig. 1.

The bolt is shown projected in Fig. 2, by 15 a spiral-spring 47 fitted to a stem 48 extended from the tongue 24 over the tail-piece 46, both passing through a bearing 34 which sustains the thrust of the spring.

20 A notch 31 is shown upon the outer side of the bolt which when retracted into the case, as shown in Fig. 1, is engaged by a spring-detent 32 which normally holds the bolt unlocked within the lock-case.

25 The tongue of the bolt is the part which engages the guard, and the tail-piece 46 is the means for guiding and steadyng the tongue when it is projected out of the case.

30 The stem 48 extends from the rear end of the bolt to the end of the tail-piece, and passes with the tail-piece through a bearing 34 which forms an abutment for the spring 47 to propel the tongue from the case when the detent is retracted.

35 The tail-piece is indicated at 46 in Fig. 1 with the stem extending above it, and the spiral-spring compressed between the bearing and the tongue.

40 It is immaterial how the arc belt is provided with the arc-shaped coil-spring.

45 This detent is attached to an elbow-piece 28 from which a rod 29 extends through bearings 34' to a beveled head 35 which projects normally from the case and moves as of one piece with the detent. These co-acting parts are termed a "releaser" herein because the contact of the beveled head with the guard pushes the detent from its notch and releases the bolt for automatic movement to its locked position, shown in 50 Fig. 2.

55 A spring 36 applied to the rod 29 presses the detent normally toward the notch 31 and presses the beveled head 35 from the case. The closing of the door any time thereafter pushes back the beveled head and withdraws the detent from the lock-bolt. It is obvious that the contact of the beveled head with the guard 22 when the door is closed, operates to push the detent from the notch 31 and to thus permit the 60 spring 47 to move the tongue 24 of the bolt into and through the apertures 25 and 26.

65 A lock-barrel 30 is journaled in the lock-case to be turned by a knob 70, and is provided with an arm 33 to engage a prong 37

upon the inner end of the tongue. A key-barrel 30' is also journaled upon the opposite side of the lock-case to be operated by a key. It is also provided with an arm 71 to engage the prong 37. When such key or lock-barrel is turned by a knob or a key respectively, and the bolt is wholly retracted the notch 31 is set opposite the detent 32, as shown in Fig. 1.

70 The detents shown operate with a notch or a projection, and it will also be understood that they may operate with complementary projections, which will have the same effect.

75 The tongue 24 is so proportioned that its opposite ends engage the lock-face within the apertures 25, and prevents the tongue from being crowded outwardly by a jimmy or other implement. When the tongue is thus engaged, it embraces the metal post 42' 80 between the apertures 26 of the guard, and binds the guard firmly to the lock-case.

85 To insure the complete interlocking of the bolt with the detent, a detent-tumbler 42 is mounted adjacent to the detent to engage the shoulder upon the detent, as shown at 90 43 in Fig. 2, which prevents the detent and releaser from projecting until the bolt has been drawn wholly within the casing.

95 This tumbler 42 is pressed toward the side of the detent by a spring 44, and has a lug 45 projecting in the path of the bolt, as shown in Fig. 1, to push the tumbler clear from the shoulder and allow the detent to 100 enter the notch 31. When this occurs, the releaser under the influence of the spring 36 upon the rod 29, presses the beveled head 35 out of the lock-case, as shown in Fig. 1, in readiness to engage the guard when the door is again closed.

105 The detent requires a considerable bearing-surface to resist its impact with the bolt, and the detent and notch 31 are made of such size and shape, that the detent may drop gradually into the notch when the bolt is fully retracted.

110 The retraction of the bolt by external means is prevented by arranging a so-called bolt-tumbler to engage a shoulder in the bolt-tongue when fully projected, which construction fully resists any return movement of the tongue when projected from the lock-case. This bolt-tumbler is actuated by an arm upon the key or lock-barrels so as to 115 be detached from the bolt before the bolt can be retracted.

120 In this arrangement, (see Fig. 11) the bolt-tumbler 60 has a tapering pawl 57 attached to a shank 58 which is movable in guides 57' and is provided adjacent to the lock-barrel with an inclined arm-seat 61.

125 The arms upon the key and lock-barrels are arranged when first moved thereby to press upon the inclined arm-seat to retract the pawl 57 from its shoulder 62 in the bolt,

freeing the bolt so that further rotation of the arms is free from further restraint while retracting the bolt into the case. The engagement of such head and shoulder blocks 5 the bolt from any movement whatever.

To retract the bolt, the key or lock-barrel is turned by hand, and the arm upon the lock-barrel pushes either the key or bolt-tumbler upward until its pawl clears the 10 shoulder 62 in the bolt.

When the bolt is wholly retracted, the end of the tail-piece reaches the point of contact (shown in Fig. 10) with the lower end of the bolt-tumbler and raises it by oblique 15 pressure.

When the operator ceases to turn the lock-barrel the leaf-spring 65 returns it to its initial position, and clears the "seat" 61 in such return movement, because the arm seat 20 is held in its raised position by the contact of the tail-piece 46 with the lower end of the bolt tumbler 57, as shown in Fig. 10.

If the door be now shut, the detent becomes disengaged from the bolt and the 25 bolt is projected from the lock-case into the guard. When the bolt is fully projected, the lower end of the bolt-tumbler engages the shoulder 62, thus locking it again in its projected position, the tumbler being first raised by the bolt-end moving across the 30 beveled end of the pawl.

In case the wood-work shrinks on which the lock-case or guard is secured, the guard would be so displaced that it would not admit 35 the tongue to its apertures; and means is therefore needed to compensate for such shrinkage, or for displacement from other causes.

In the mortise-lock shown in Fig. 2, the 40 face-plate 66 of the guard is clamped to the door-frame 23 by screws 67, and the guard is provided with loose packing-plates or shims 68 shown underneath the ends of the guard where the screws pass through the 45 same.

The effect of such shims is to raise the face of the plate somewhat above the surface of the wood-work, if recessed therein as is 50 usual. Such raising of the face-plate 66 exposes its edge to access by a jimmy which is prevented by beveling the edges of the plate, as shown at 69 in Figs. 2, 6 and 11.

In Fig. 11 the bolt-chamber 63 in the 55 guard has a rear wall curved like the bolt-tongue, to increase the strength of the guard and protect it from dirt and dust.

In the rim-lock shown in Fig. 9, the guard is preferably made in two pieces 50 and 51, one of which has a bed-piece 52 attached rigidly to the door-frame, and the other carries the striking-plate 53 and has a foot 54 secured adjustably to the bed-piece by a screw 55.

The parts are formed with corresponding 60 ridges 57 which hold them firmly in their

adjusted positions, and permit of readjustment by the slackening of the clamp-screws.

By the use of the detent-tumbler described, only the last portion of the retracting movement of the bolt has any releasing 70 effect upon the detent, or secures any engagement of the detent with the notch.

It is obvious that when the lock-barrel is turned the bolt may be locked in its retracted position by any form of projecting or complementary parts which operates the same as the detent and the notch. 75

It will be observed that the lock operates automatically to lock the door whenever it is closed, by the action of the releaser upon 80 the detent. 80

Fig. 11 shows a couple of push-buttons 39 and 40 fitted movably through the face-plate 66 of the lock, one of which presses a push-rod 39' adapted to engage a shoulder or 85 notch 40' upon the inner side of the bolt, when the tongue is wholly retracted. The other push-button is formed upon a shank 41 which is connected with the rod 39' by a simple lever 19, which enables the first push-button to be projected by pressing the second inwardly. 90

The bolt-tongue has a member, such as a notch 40' which is moved in line with the rod 39' when the bolt-tongue is retracted. 95 The pushing of such rod into the notch holds the bolt from any movement.

From the above description it will be seen that this invention automatically interlocks the door and door-jamb, and affords the utmost resistance to forcing the lock by external means. 100

Having thus set forth the nature of the invention what is claimed herein is:

1. The combination, with a lock having an arc-bolt movable into and out of its face, of means to project the bolt, means to hold the bolt in its projected position, means to retract the bolt, means to hold the bolt in its retracted position, and a guard having 105 adjustable parts for varying the relative positions of the lock and guard. 110

2. A lock having an arc-shaped bolt, a guide for the bolt, means for projecting the bolt, means for automatically locking the bolt in its projected position, independent barrels operating to retract the bolt, a detent to engage the bolt and hold the bolt retracted, a releaser to disengage the detent from the bolt, means to hold the bolt inoperative when retracted, and an adjustable guard to interlock with the bolt. 115 120

3. The combination, with a guard, of a lock-case having an arc-bolt with means to project and hold the bolt in its projected position, means to retract the bolt, a detent to engage the bolt, a releaser adapted to project from the lock-case and to disengage the detent, means to project said releaser, a tumbler arranged and operated to prevent 125 130

the releaser from projecting from the lock-case until the bolt is wholly retracted.

4. The combination, with a lock-case having an arc-bolt with a tongue movable into and out of its face, of a guard to engage such tongue, a detent for securing the bolt in its unlocked position, a releaser in one piece with the detent and having a beveled head to engage the guard when the door is closed, thus releasing the bolt for automatically locking, and a tumbler having automatic means to hold the bolt in its projected position, and a catch to hold the bolt inoperative.

15. The combination, with a guard, of a lock-case having an arc-bolt with a tongue movable into and out of said lock-case, a raceway having ribs to guide the bolt in its movement, a tail-piece projected from the bolt to engage the raceway, means for projecting and retracting the bolt and locking it in its inoperative position, a detent to engage the bolt, and a releaser to disengage the detent.

25. The combination, with a lock-case having an arc-bolt movable into and out of its face, of a raceway having ribs to guide the bolt in its movement, a tail-piece upon the bolt fitted to the raceway, a detent and tumbler for holding the bolt detachably unlocked, a stem projected from the rear end of the bolt and a spring fitted to said stem to project the bolt normally from the lock-case, a releaser to operate the detent, and means to retract and hold the bolt inoperative.

40. The combination, with a lock-case having an arc-bolt movable into and out of its face to engage a guard, of a detent for securing the bolt in its unlocked position, the said detent and bolt having complementary projections to automatically engage one another for holding the bolt unlocked, and a stem projected from the bolt, and provided with a spring to project the bolt normally from the lock-case, a suitable guard for engaging the bolt when projected, means to automatically lock the bolt in its projected position, means to retract the bolt, and means to hold the bolt inoperative.

55. The combination, with a lock-case having a suitable raceway therein, of an arc-bolt having a tail-piece fitted movably to the raceway and a tongue for engaging the guard, a stem projected from the bolt and provided with a spring to project the bolt normally from the lock-case, the lock having a suitable guard, means to retract the bolt operable either by a key or by a knob, a tumbler to hold the bolt projected, a detent having means to engage and to disengage the bolt, and a catch to hold the bolt retracted and inoperative.

60. A lock having an arc-bolt, a guide for the bolt, a detent to engage the bolt, a re-

leaser to release the detent, means to operate the detent and hold the bolt retracted, means to automatically project the bolt and hold the bolt in its projected position, and means to hold the bolt inoperative.

70. 10. The combination, with a lock-case having an arc-bolt with a tongue movable into and out of said lock-case to engage a guard, of a detent for securing the bolt in its unlocked position, said detent and bolt having complementary projections to automatically engage one another for holding the bolt unlocked, means to project the bolt and hold it projected, means to retract said bolt and means to hold the bolt inoperative.

15. 11. In a lock having a guard fitted upon a door-jamb, means for protecting the face-plate from access and engagement by a jimmy or other tool, which consists of a recess in the door-jamb to which the face-plate is fitted, and beveled edges upon the face-plate to avoid the exposure of its edges when the face-plate is raised in its recess.

20. 12. The combination, with a lock case having a curved bolt, of a guard or striking-plate having beveled edges arranged and operated for the purpose set forth.

25. 13. A lock having an arc-shaped bolt, means for projecting the bolt, means for retracting the bolt, a detent to engage the bolt, a tumbler to engage the detent, a releaser to disengage the detent from the bolt, means to project the releaser, means to disengage the detent-tumbler from the releaser, and a guard to engage the bolt and the releaser.

35. 14. A lock having an arc-shaped bolt, means for projecting said bolt and means to retract the same, and means engaging the side of said bolt for automatically holding said bolt in its projected position.

40. 15. A lock having an arc-shaped bolt, a shoulder on said bolt and means engaging said shoulder disposed interiorly of the path of movement of said bolt to hold the same projected.

45. 16. A lock having an arc-shaped bolt, means for engaging said bolt for holding the same in its retracted position, and automatic means for controlling the movement of said first mentioned means.

50. 17. A lock having an arc-shaped bolt, a detent for engaging said bolt and automatic means for controlling the movement of said detent.

55. 18. A lock having an arc-shaped bolt, means for engaging said bolt to hold the same retracted, and automatic means for controlling the movement of said first-mentioned means.

60. 19. A lock having an arc-shaped bolt, a detent for engaging said bolt to hold the same retracted and a tumbler for limiting the movement of said detent.

65. 20. A lock having an arc-shaped bolt, a

detent for engaging said bolt, and a tumbler for engaging said detent.

21. A lock having an arc-shaped bolt, a detent for automatically engaging said bolt and a movable member for automatically engaging said detent.

22. A lock having an arc-shaped bolt, means for holding said bolt in its retracted position, and automatic means for controlling and limiting the movement of said first-mentioned means.

23. A lock having an arc-shaped bolt, a detent cooperating with said bolt, and means cooperating with said detent and bolt to prevent interference of the former with the latter during retraction of the bolt.

24. A lock having an arc-shaped bolt, a detent cooperating with said bolt, and means cooperating with said detent and bolt to prevent interference of the former with the latter during retraction of the bolt, said means also assuring the proper engagement of the detent with the bolt to hold the same retracted.

25. A lock having an arc-shaped bolt, a detent cooperating with said bolt to hold the same retracted, and means controlled by the movement of the arc-shaped bolt to assure engagement of the detent therewith when it reaches the proper position.

26. A lock having an arc-shaped bolt, a detent cooperating with said bolt to hold the same in its retracted position, and means engaging said detent to prevent the same from interfering with the movement of said bolt.

27. A lock having an arc-shaped bolt, a detent cooperating with said bolt to hold the same in its retracted position, and means engaging said detent to prevent the same from interfering with the movement of said bolt and operated by said bolt to release the detent when the bolt is fully retracted.

28. A lock having an arc-shaped bolt, a detent for holding the bolt retracted and automatic means to prevent said detent from interfering with said bolt during its movements and to assure the detention of the bolt when normally retracted.

29. A lock having an arc-shaped bolt, means to retract said bolt, a detent, means to limit the operation of said detent when partially moved, and means to permit the complete movement of said detent, both of said means assuring the normal retraction and detention of the bolt.

30. A lock having an arc-shaped bolt, means to retract said bolt, and means engaging the bolt to hold the same inoperative.

31. A lock having an arc-shaped bolt, means to retract said bolt, and a catch to hold the bolt inoperative when in its retracted position.

32. A lock having an arc-shaped bolt,

means to retract said bolt, means to project said bolt, a detent directly engaging said bolt for normally holding said bolt in its retracted position, means for holding said detent in a given position, means for releasing said detent and means for rendering said releasing means ineffective.

33. A lock having an arc-shaped bolt, means to retract said bolt, means to project said bolt, a detent for normally holding said bolt retracted, means for releasing said detent, and means engaging said bolt and operable manually to dog said bolt, whereby said releasing means is rendered ineffective.

34. A lock having an arc-shaped bolt, means for projecting said bolt, means for locking said bolt in its projected position, means for retracting said bolt, said last-mentioned means operating to first release said lock means and then to retract said bolt, said bolt having a portion thereof engaging said locking means to hold said bolt in retracted position so that the return of said retracting means to normal position meets with no interference.

35. A lock having an arc-shaped bolt, means to retract said bolt, means to project said bolt, a detent for normally holding said bolt retracted, means for releasing said detent, means engaging said bolt and operable manually to render said releasing means ineffective, and means for disengaging said manually operable means.

36. A lock having an arc-shaped bolt, means for projecting said bolt, means for locking said bolt in its projected position, a common means for disengaging said locking means and for retracting said bolt, means for returning said common means to its initial position, all of said means and said bolt being so arranged as to offer no interference to the return of said common means to its initial position at any point in its movement.

37. A lock having an arc-shaped bolt, means for projecting said bolt, means for locking said bolt in its projected position, means common to said locking means and said bolt for first unlocking said locking means and then for retracting said bolt, the parts being so arranged as to permit return of said common means to its initial position without interference at any point in its movement, and means for returning said common means to its initial position.

38. A lock having an arc-shaped bolt, means for projecting said bolt, means for locking said bolt in its projected position, means cooperating with said locking means to unlock the same and then to directly engage said bolt to retract the same, said last mentioned means engaging said locking means until said bolt engages the same to hold said locking means out of locking en-

gagement therewith, and means for returning said unlocking means to its initial position.

39. A lock having an arc-shaped bolt, means for projecting said bolt, means for locking said bolt in its projected position, means cooperating with said locking means for disengaging the same from said bolt, said means directly engaging said bolt to 10 retract the same, and a spring for returning said last mentioned means to its initial position.

40. A lock having an arc-shaped bolt, means for projecting said bolt, a barrel 15 having means for retracting said bolt, means for holding said bolt in its projected position, said barrel cooperating with said last mentioned means to disengage the same from engagement with said bolt, and a 20 spring to return said barrel to its initial position.

41. A lock having an arc-shaped bolt, means for projecting said bolt, means for locking said bolt in its projected position, 25 a barrel cooperating first with said locking means to unlock the same and then with said bolt to retract the same, and means comprising a coil spring for returning said barrel to its initial position.

42. A lock having an arc-shaped bolt and a tumbler having means for engaging the bolt to hold the same in its projected position, and a lock barrel having direct means for disengaging said bolt and tumbler.

43. An arc-shaped bolt and a tumbler having means for interlocking with the bolt to hold the latter in its projected position, and a lock-barrel having an arm for unlocking said bolt and tumbler.

44. An arc-shaped bolt and a tumbler having means for engaging a notch on said bolt for holding the latter in its projected position.

45. An arc-shaped bolt having an arc stem, a spring adjusted to said stem, and means to hold said bolt in its projected position.

46. A lock, comprising a lock barrel having means for automatically returning the same to its initial position.

47. In a lock, a lock-barrel having a coiled leaf spring, said spring operating to return said barrel to its initial position.

48. An arc-shaped bolt, means for projecting said bolt, means to hold said bolt projected, a lock barrel having means to directly release said holding means, means to retract the bolt, and means to return said lock-barrel to its initial position without the return of the bolt to its projected position.

49. A lock having an arc bolt comprising a tongue portion, a stem, a spring, and means to hold the bolt inoperative.

50. A lock comprising a casing, an arcuate

bolt, means to project said bolt, and means operable from the face of said casing to hold said bolt inoperative.

51. The combination with a guard, of a lock-case having an arc-bolt with a tongue 70 movable into and out of said case, a race-way for guiding said bolt in its movements, a tail-piece projecting from said bolt to engage said raceway, means for projecting and retracting said bolt and for locking it in its 75 inoperative position, and a detent to hold said bolt retracted.

52. A lock having an arcuate bolt and means disposed within the arc defined by said bolt for holding the same inoperative. 80

53. A lock having a casing, an arc bolt adapted to be projected from said casing, and a key-cylinder fastened in said casing and having direct connection with said bolt to actuate the same.

54. A lock comprising a casing, an arc bolt, means to project said bolt, means to retract said bolt, a common means to hold said bolt retracted and to release said bolt for projection and means to hold said bolt 90 inoperative.

55. A lock having an arc-shaped bolt consisting of a bolt portion, a tail portion and a stem for a spring overlying said tail portion.

56. A lock having an arc bolt, a slidable bolt tumbler, and a slidable detent cooperating with said tumbler.

57. In a lock, a casing, an arc bolt, means to project said bolt, means to retract said bolt, means directly engaging said bolt to hold the same retracted and which is adapted to release said bolt, and means to render ineffective said releasing means.

58. An arc bolt lock comprising an arc 105 bolt, means to project said bolt, means to retract said bolt, common means to hold said bolt retracted, and to release the same for projection, and means to render said common means ineffective.

59. A lock having an arc bolt, a guideway to direct the bolt in an arcuate path, means to project the bolt, means to hold said bolt projected, and a key cylinder to actuate said bolt.

60. A lock having an arc bolt, a guideway to direct the bolt in an arcuate path, and a key cylinder lock to operate said bolt.

61. A lock having an arc-shaped bolt, means for holding the bolt in its projected 120 position, and a lock-barrel having means for directly releasing said holding means.

62. A lock comprising a casing, a bolt movable in a curved path and carried by said casing, and a cylinder lock for actuating said bolt, said cylinder lock having the casing thereof extended into the lock casing.

In testimony whereof I have hereunto set my hand.

CLIVE W. LANPHERE.

DISCLAIMER.

1,543,930.—*Clive W. Lanphere*, New York, N. Y. INTERLOCKING AUTOMATIC LOCK.
Patent dated June 30, 1925. Disclaimer filed October 18, 1927, by the *patentee*.

Hereby enters this disclaimer to those claims in said specification which are in the following words, to wit:

“ 16. A lock having an arc-shaped bolt, means for engaging said bolt for holding the same in its retracted position, and automatic means for controlling the movement of said first mentioned means.

“ 17. A lock having an arc-shaped bolt, a detent for engaging said bolt, and automatic means for controlling the movement of said detent.

“ 18. A lock having an arc-shaped bolt, means for engaging said bolt to hold the same retracted, and automatic means for controlling the movement of said first-mentioned means.”

“ 25. A lock having an arc-shaped bolt, a detent cooperating with said bolt to hold the same retracted, and means controlled by the movement of the arc-shaped bolt to assure engagement of the detent therewith when it reaches the proper position.”

“ 30. A lock having an arc-shaped bolt, means to retract said bolt, and means engaging the bolt to hold the same inoperative.

“ 31. A lock having an arc-shaped bolt, means to retract said bolt, and a catch to hold the bolt inoperative when in its retracted position.”

“ 42. A lock having an arc-shaped bolt and a tumbler having means for engaging the bolt to hold the same in its projected position, and a lock-barrel having direct means for disengaging said bolt and tumbler.

“ 43. An arc-shaped bolt and a tumbler having means for interlocking with the bolt to hold the latter in its projected position, and a lock-barrel having an arm for unlocking said bolt and tumbler.”

“ 52. A lock having an arcuate bolt, and means disposed within the arc defined by said bolt for holding the same inoperative.”

“ 61. A lock having an arc-shaped bolt, means for holding the bolt in its projected position, and a lock-barrel having means for directly releasing said holding means.”
